(57) CLAIM

The ornamental design for a speaker grill, as shown and described.

DESCRIPTION

FIG. 1 is a perspective view of a speaker grill, showing my design;

FIG. 2 is an opposing perspective view thereof;

FIG. 3 is front view thereof;

FIG. 4 is a rear view thereof;

FIG. 5 is a side view thereof;

FIG. 6 is an opposing side view thereof;

FIG. 7 is a top view thereof; and,

FIG. 8 is an exploded side view thereof.

The broken lines showing the environment are for illustrative purposes only and form no part of the claimed design.
